Primary Examiner — Cynthia Ramirez*(74) Attorney, Agent, or Firm* — Bay State IP, LLC(57) **CLAIM**

The ornamental design for a diaper pail, as shown and described.

DESCRIPTION

FIG. 1 is a perspective view showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a perspective view in an open configuration; and,

FIG. 9 is a perspective view in another open configuration. The broken lines illustrate environmental structure and form no part of the claimed design.

1 Claim, 9 Drawing Sheets(56)
